Fig. 6.

Fig. 7.

Fig. 8.

FIGURE 1 is a top plan view of a service station unit embodying my new design;

FIGURE 2 is a front elevation thereof;

FIGURE 3 is a rear elevation thereof;

FIGURE 4 is a side elevation thereof as viewed from the right of FIGURE 2;

FIGURE 5 is a side elevation thereof as viewed from the left of FIGURE 2;

FIGURE 6 is a fragmentary horizontal sectional view taken through the building portion of the service station unit along the line 6-6 of FIGURE 2;

FIGURE 7 is a fragmentary elevation to enlarged scale of a portion of the shadow block wall seen in FIGURE 2; and

FIGURE 8 is a fragmentary horizontal section view taken along the line 8-8 of FIGURE 7.

The dominant features of the design reside in the portions shown by means of full lines in the drawing.

I claim:

The ornamental design for a service station unit, as shown and described.
